(57) **CLAIM**

The ornamental design for a tablet case, as shown and described.

DESCRIPTION

FIG. 1 is a front, right, and bottom perspective view of a tablet case, showing my design.

FIG. 2 is a rear, right, and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a rear, left, and top perspective view thereof, comprising a supporting plate of the tablet case in an open state.

The broken lines shown in the drawings are included for the purpose of illustrating portions of the tablet case that form no part of the claimed design.
